UNITED STATES PATENT OFFICE.

PETER RASMUSSEN AND MANUEL F. GOULARTE, OF SELMA, CALIFORNIA.

TENSIONING DEVICE FOR SEWING-MACHINES.

1,247,327.

Specification of Letters Patent.

Patented Nov. 20, 1917.

Application filed October 12, 1914, Serial No. 866,382. Renewed May 10, 1917. Serial No. 167,804.

To all whom it may concern:

Be it known that we, PETER RASMUSSEN and MANUEL F. GOULARTE, citizens of the United States, residing at Selma, in the 5 county of Fresno and State of California, have invented certain new and useful Improvements in Tensioning Devices for Sewing-Machines, of which the following is a specification, reference being had to the accompanying drawings.

This invention relates to an improved thread tensioning device for sewing machines and more particularly to a device of this character which is commonly employed 15 in connection with shoe sewing machines.

The present invention has for its primary object to produce a simple, reliable, and effective tensioning means for machines of the above character which may be easily and 20 quickly adjusted to vary the tension upon the thread.

The invention has for another object to provide a tension regulating device which is simple and durable in its construction, is 25 not liable to get out of order, and may be manufactured at comparatively small cost.

With the above and other objects in view, our invention consists in the novel features of construction, combination, and arrangement of parts to be hereinafter more fully 30 described, claimed, and illustrated in the accompanying drawing, in which,

Figure 1 is a front elevation showing our improved thread tensioning device in its preferred embodiment;

Fig. 2 is a side elevation;

Fig. 3 is a section taken on the line 3—3 of Fig. 2;

Fig. 4 is a section taken on the line 4—4 of Fig. 2; and

Fig. 5 is a detail perspective view of one of the parts.

Referring in detail to the drawing, 5 designates a stationary bar which is suitably 45 mounted upon the frame of the machine and secured in place by means of bolts indicated at 6. This bar is provided with a widened end portion 7 having an obliquely inclined edge face indicated at 8. From the inner 50 end of this inclined face of the bar 5, the edge of the bar is inwardly curved as at 9, said curved edge extending through an arc of substantially 90°. The bar 5 is slightly reduced in width from one end of this curve 55 to a point in spaced relation to the end of the bar, as indicated at 10. Adjacent to the

end of this latter portion of the body bar 5, a guide eye 11 is secured therein. The curved edge 9 and the reduced portion 10 of the bar 5 has integrally formed thereon 60 a continuous longitudinally extending rib 12, the purpose of which will be hereinafter pointed out.

A cast metal plate 13 of channel-shaped form in cross-section is provided with ears 65 14 upon its parallel side walls at one of their ends which are pivotally mounted as at 15 upon the widened end 6 of the bar 5. The parallel walls or flanges 16 of this channel-shaped casting are spaced apart a sufficient 70 distance to receive between them the body bar 5, when said casting is arranged in substantial parallel relation to the same. The connecting wall 13' between the flanges 16 is cut away for a portion of its length to produce a slot 17, and upon the corresponding edges of the flanges 16 and projecting outwardly from said slot, the ears 18 are formed. Between these ears a peripheral 75 grooved thread guide wheel or roller 19 is 80 rotatably mounted. The transverse connecting wall 13' between the flanges 16 is further provided adjacent to its outer end with an opening 20. This opening is adapted to receive a threaded bolt 21 which is fixed at one 85 of its ends in the relatively narrow end portion of the body bar 5. A coil spring 22 is arranged upon said bolt and disposed between said bar and the intermediate wall 13' of the channel casting 13. 23 indicates an 90 adjusting nut which is threaded upon the end of the bolt 21 and bears against the wall 13'. The casting 13 may be readily adjusted with respect to the bar 5 by turning said nut.

It will be observed from reference to Figs. 95 1 and 4 of the drawing, that the guide eye 11 on the bar 5 projects outwardly through the slot 17 in the casting 13 and is slightly spaced from the grooved wheel 19.

In the use of our invention, the thread indicated at T is passed through this eye and under the wheel 19 between the same and the longitudinally extending rib 12 formed upon the edge of the bar 5. The thread is then passed over the beveled or inclined edge face 100 8 of said bar to the bobbin or spool upon which it is adapted to be wound. By now screwing the nut 23 inwardly upon the bolt 21, the casting 13 which carries the wheel 19 105 will be forced inwardly toward said bar, and the rib 12 thereon received in the peripheral groove of the wheel 19. This rib exerts a 110

pressure or tension upon the thread as it passes around said wheel. In this manner, it will be understood that liability of kinking or raveling of the thread as it is wound upon the bobbin, is obviated. The pressure of the rib 12 upon the thread may be very easily and quickly varied by simply manipulating the nut 23.

From the foregoing description, taken in connection with the accompanying drawing, the construction, manner of use, and several advantages of our invention will be clearly and fully understood. The device may be readily mounted upon shoe sewing machines of the type now in general use without necessitating any material alterations in their construction. It will not lose its efficiency after a short period of use as is the case with tensioning devices employing leaf springs or analogous resilient thread engaging elements. As the rib 12 fits within the groove of the guide wheel over which the thread passes, it will also be manifest that this rib will effectually prevent all possibility of the thread becoming disengaged from the groove of the wheel in the operation of the machine. As our invention consists of very few parts which are all of simple form, it will further be appreciated that the device can be constructed at small manufacturing cost.

While we have above described the preferred construction and arrangement of the several elements employed, it will be understood that the device is susceptible of considerable modification therein and we therefore reserve the privilege of resorting to all such legitimate changes as may be fairly embodied within the spirit and scope of the invention as claimed.

Having thus described our invention, what we desire to claim and secure by Letters Patent is:—

1. A thread tensioning device including a body bar provided upon one edge with a longitudinally extending rib, a wheel carrying element adjustably mounted upon said bar, a peripherally grooved guide wheel for the thread mounted upon said element, and means mounted upon said bar for adjusting said element with respect to the bar to en-

gage the rib within the groove of said wheel and upon the thread.

2. A thread tensioning device including a body bar, a channel-shaped member pivotally mounted at one of its ends upon said bar, the opposed walls of said member being disposed upon opposite sides of the bar, said channel-shaped member being provided with a slot in its intermediate wall, a peripherally grooved guide wheel for the thread mounted upon said member and extending into said slot, a longitudinally extending rib on the edge of the body bar, and means for adjusting said channel-shaped member upon the bar to dispose said rib within the groove of the guide wheel and upon the thread.

3. A thread tensioning device including a body bar having a longitudinally curved edge portion and provided thereon with a rib, said rib extending beyond the curved portion of the bar longitudinally thereof, a channel-shaped member pivotally mounted at one of its ends upon the body bar, a peripherally grooved guide wheel carried by said member, the groove of said wheel being adapted to receive the curved portion of said rib, a guide eye fixed in said bar, and means for adjusting said channel-shaped member upon the body bar to vary the pressure of said rib upon the thread in the groove of the guide wheel.

4. A thread tensioning device including a fixed body bar, a channel-shaped element movably mounted upon said body bar, a thread guide mounted upon said element and projecting into the channel of said element, means for adjusting said element to position the thread guide with respect to the bar, and means on said bar to exert a tensioning pressure on the thread in an adjusted position of the guide.

In testimony whereof we hereunto affix our signatures in the presence of two witnesses.

PETER RASMUSSEN.
MANUEL F. GOULARTE.
